UNITED STATES PATENT OFFICE.

WILLIAM ILE, OF TORONTO, ONTARIO, CANADA.

ELECTRIC PLUG-RECEPTACLE.

1,300,270.

Specification of Letters Patent. Patented Apr. 15, 1919.

Application filed February 19, 1917. Serial No. 149,458.

To all whom it may concern:

Be it known that I, WILLIAM ILE, a subject of the King of Great Britain, and resident of the city of Toronto, county of York, Province of Ontario, in the Dominion of Canada, have invented certain new and useful Improvements in Electric Plug-Receptacles, as described in the following specification and illustrated in the accompanying drawings, that form part of the same.

The principal objects of the invention are, to provide a neat and simple form of plug receptacle for use in electrical fittings which will be extremely neat in appearance and will be very rigid and the parts will not be susceptible of working loose and causing electrical troubles.

The principal feature of the invention consists in the novel construction and arrangement of an electrical plug and a plurality of socket members electrically connected therewith, whereby the whole is united in a rigid and compact unit, the electrical connections of the shells of the plug and sockets being effectively separated from the central electrical connection.

In the drawings, Figure 1 is a side elevational view of a receptacle constructed according to this invention.

Fig. 2 is a vertical sectional view through the receptacle.

Fig. 3 is a detail perspective view of the porcelain plug of the upper member being shown bottom side up.

Plug receptacles have been marketed for a long time formed of a number of parts secured together in various manners but it is believed that all of these have the common fault of working loose and forming bad electrical contacts which are extremely dangerous.

According to the present invention the plug 1 is formed of a porcelain block 2 and a threaded metal casing 3. The block 2 is formed with a central hole 4 countersunk at the top and a recess 5 is formed in the bottom end to receive the flat metal member 6.

7 are notches or recesses formed in the lower edge of the block 2 into which the bottom edge of the metal casing 3 is indented.

The upper end 8 of the metal casing is flanged inwardly to engage the top of the block 2. When the lower edge is indented into the notches in the block the metal becomes firmly secured to the porcelain. The

flat metal member 6 fits snugly in the recess 5 and is provided with a central hole 9 through which a bolt 10 which passes through the central hole 4 in the block 2 extends.

A nut 11 is threaded on the lower end of the bolt 10 and locks the member 6 in place. The recess 5 is preferably of circular form so that the top of the metal member 6 may be placed in same. The circular recess is adapted to receive the top of the central member adapted for a three or four socket receptacle. The member 6 is bent downwardly and is provided with laterally turned ends 12 which are adapted to receive the center contact member 13.

14 are socket shells formed of spun sheet metal threaded and having inwardly turned flanges 15 at the top with a large center hole 16.

17 are disks of insulating material fitted into the interior of the socket shells 14 at the top end and abutting the flanges 15, and 18 are corresponding disks arranged at the outer side of the flanges 15.

The contact members 13 pass through the disks 17 and 18 into the ends 12 of the member 6 and bind the said disks together holding the sockets firmly and as the said disks are of insulating material the shells are effectively insulated.

The socket shells 14 are electrically connected with the plug casing 3 by means of metal strips 19 which have flanged ends 20 which fit into the indented portions of the said casing 3 bent into the notches. These are firmly soldered in place.

The structure thus formed is then incased in a surrounding jacket of insulating material such as bakelite which is molded around the receptacle shells and around the bottom ends of the threaded plug casing.

All the parts are firmly embedded in a rigid block so that they cannot work loose or become disconnected. The bolt 10 with the strips 6 and members 13 form the central electrical connections to the lamps or other plugs secured in the sockets and the outer shells and threaded metal casing are distinctly and entirely electrically separated from the central connections.

What I claim as my invention is:—

1. A plug receptacle, comprising, a plug of insulating material having a single hole 110 extending therethrough from end to end, a threaded metal casing encircling a portion

- of said plug, a bolt extending through the hole in said plug, a metal member secured to said bolt and carrying branch electrical contacts, socket shells connected with, and insulated from, said central metal member, flexible electrical connections secured to the exterior of said socket shells and to the inward end of the plug casing, and a unitary mass of insulating material surrounding 10 said socket shells and the inward end of the plug casing and completely embedding the electrical connections between the plug and the sockets.
2. A plug receptacle, comprising, a circular plug having notches in the edges and a central orifice and a recess in the bottom communicating with said orifice, a threaded metal casing surrounding said plug and having indents extending into said notches, a bolt extending through the central orifice in said plug, a central metal member secured on said bolt and fitting in said recess, said central member extending angularly outward from said plug and having laterally turned ends, a pair of insulating disks secured to each of the ends of said
- central member, socket shells held between said insulating disks, metal strips connected to said socket shells and to said plug casing, and a mass of insulating material molded around said shells and the lower end of said plug and incasing the intermediate connections.
3. A plug receptacle, comprising, a plug of insulating material threaded externally and having a recess in the inner end, a threaded metal casing encircling said plug, a bolt extending through said insulated center, a metal member secured to said bolt and fitting into the recess in said plug, 35 threaded metal socket shells having inturned flanges at the upper ends, metal strips rigidly secured at one end to said plug casing and at the other end to the flange ends of said socket shells, central contacts for 40 each of said sockets secured to the central metal member and insulated from said casings, and a unitary mass of insulating material molded around and embedding said shells and electrical connections.

WILLIAM ILE.
